UNITED STATES PATENT OFFICE

152,931

DESIGN FOR A COMBINED WASHING
MACHINE AND WRINGER

Clarence Gilbert Taylor, Alliance, Ohio

Application January 21, 1947, Serial No. 136,277

Term of patent 7 years

(Cl. D49—1)

To all whom it may concern:

Be it known that I, Clarence Gilbert Taylor, a citizen of the United States, residing at Alliance, in the county of Stark and State of Ohio, have invented a new, original, and ornamental Design for a Combined Washing Machine and Wringer, of which the following is a specification, reference being had to the accompanying drawing, forming part thereof.

Fig. 1 is a front elevational view of a combined washing machine and wringer embodying my new design;

Fig. 2 is a side elevational view thereof;

Fig. 3 is a top plan view; and

Fig. 4 is a fragmentary, front elevation of the upper portion of the washing machine handle.

I claim:

The ornamental design for a combined washing machine and wringer, as shown.

CLARENCE GILBERT TAYLOR.
